(57) **CLAIM**

The ornamental design for a zippered pouch, as shown and described.

DESCRIPTION

FIG. 1 is a top perspective view of a zippered pouch, showing my new design in a closed configuration; FIG. 2 is a top perspective view thereof, illustrated in an open configuration;

FIG. 3 is a left-side elevational view of FIG. 2, the right-side elevational view being a mirror image thereof;

FIG. 4 is a front elevational view of FIG. 2;

FIG. 5 is a rear elevational view of FIG. 2;

FIG. 6 is a top plan view of FIG. 2;

FIG. 7 is a bottom plan view of FIG. 2; and,

FIG. 8 is a cross-sectional view thereof, taken along line 8-8 of FIG. 6.

The broken lines in FIG. 2 showing a sexual aid depict environmental matter that forms no part of the claimed design. The remaining broken lines depict stitching, and do form part of the claimed design.
